APPARATUS FOR RAISING SUNKEN VESSELS,

APPLICATION FILED APR. 17, 1918.

1,274,004.

Patented July 30, 1918.

2 SHEETS—SHEET 2.

By his Attorney Charles Christie
Hansard Bissell

UNITED STATES PATENT OFFICE.

CHARLES CHRISTIE, OF FORDS, NEW JERSEY.

APPARATUS FOR RAISING SUNKEN VESSELS.

1,274,004.

Specification of Letters Patent. Patented July 30, 1918.

Application filed April 17, 1916. Serial No. 228,996.

To all whom it may concern:

Be it known that I, CHARLES CHRISTIE, a citizen of the United States, and a resident of Fords, in the county of Middlesex and State of New Jersey, have invented certain new and useful Improvements in Apparatus for Raising Sunken Vessels, of which the following is a specification.

This invention relates to an apparatus of novel construction, that is adapted to be submerged in proximity to the vessel to be raised, and is provided with means for attaching a number of grappling hooks to said vessel. By my invention, these hooks may be accurately placed wherever desired, the entire operation of connecting the wreck to the hooks, being under the full control of the operator. The invention further comprises various other features of novelty all as more fully pointed out in the specification and appended claims.

In the accompanying drawing:

Figure 1 is a vertical longitudinal section of a submarine boat, embodying my invention;

Fig. 2, a plan thereof;

Fig. 3, a plan partly in section, of the hook-setting device;

Fig. 4, a section on line 4—4 Fig. 3;

Fig. 5, a section on line 5—5 Fig. 3, and

Fig. 6, a plan partly in section of one of the diving plates.

A submarine boat 1 is provided with propellers 2, at its bow and stern, as well as along its keel and deck, so that it may be propelled in all directions, and may thus be moved into proximity to the wreck to be raised. The boat is furnished with an air pipe 3, rudders 4, telephone wires 5, and various other equipment not necessary to be further specified.

In order to assist the diving movement of the boat, it is provided near each of its ends with a longitudinally tiltable plate 6, extending across the same at a distance below its keel. Each plate is pivotally suspended from the boat by a pintle 7, that turns in a bearing 8 extending across the keel, the pintle engaging the knuckle of an open-work angular frame or hinge-leaf 9, to which plate 6 is secured. A screw spindle 10 tapped in a bearing 11 and adapted to bear against the rear end of plate 6, serves to limit or check its tilting movement.

When the boat dives, bow foremost, plates 6 will, owing to the forward water pressure,

assume a corresponding upward dip from front to rear, and thus assist in the diving movement. As soon as the boat strikes bottom, and the pressure relaxes, the plates will resume their normal horizontal position, and will now constitute supports that sustain the boat, while the keel remains free and clear. Through each side of boat 1, there extend means for engaging grappling hooks and for guiding said hooks into engagement with the vessel to be raised, the hooks being suspended by ropes or chains from a suitable hoist, mounted on an additional vessel, which is afloat, and does not form part of the present invention. With the embodiment shown, four hook-operating devices project from each side of the vessel, each device being placed in proximity to a port hole 12, so that its operation may be readily observed. A drill 13, may also be fitted to the boat, by means of which the wreck may be punctured, for engagement with the hooks, whenever it should not be feasible to pass the latter into port holes or other holdfasts.

Each hook-operating device comprises a rectangular slidable frame A composed of a pair of side bars 14, 15, a rear end bar 16, and a front end bar 17. Bars 14, 15 pass through openings formed in the sides of vessel 1, said openings being provided with water tight packings 18. The rear end bar 16 has a screw eye 19 engaging a longitudinally disposed lag screw 20, the headed end 21 of which engages a socket 22, fastened to the inner side of vessel 1, so that by turning the screw by means of a handle 23, frame A may be slid outward or inward to any extent desired. One of the longitudinal bars 14, 15, say the bar 15, is made hollow or tubular for the reception of an axially rotatable shaft 24, the forward end of which extends a distance beyond bar 17, and is here bent at right angles to constitute a finger 25 that parallels bar 17. Shaft 24, may be turned by means of a handle 26, so that finger 25 may be swung either toward or away from bar 17. To bars 14, 15 there is furthermore pivoted at 27, a pair of jaws 28, that are drawn together by a spring 29 and project beneath rod 17 a distance beyond finger 25.

In operation, the grappling hook 30, suspended by a cable or chain 31 from the hoist hereinabove referred to, is engaged by jaws 28, and rock shaft 24 is turned so as to throw finger 25 opposite to bar 17, and into

the bight of the hook, so that the latter is tightly clamped between said finger and bar 17. The frame is now slid outward, by turning screw 20 until the beak of the hook is 5 projected into the port hole 32 or other opening of the vessel 33 to be raised. Rock shaft 24 is now turned in the opposite direction, to throw finger 25 clear of hook 30, and screw 20 is turned to retract frame A, and thus 10 cause jaws 28 as well as bar 17 to likewise clear the hook. After all the hooks have thus been entirely disconnected from their frames, the winches are operated to raise the wreck.

15 I wish it to be understood that the submarine boat 1, may be replaced by a diver's bell or similar submersible casing.

I claim:

1. A device of the character described,

comprising a submersible casing, a slidable 20 frame carried thereby, and a finger rotatably secured to said frame.

2. A device of the character described, comprising a submersible casing, a slidable frame carried thereby, a finger rotatably 25 mounted on the frame, and a pair of jaws pivoted to the frame.

3. A device of the character described, comprising a submersible casing, a slidable frame carried thereby, said frame being composed of a pair of side bars, a front bar, and a rear bar, one of the side bars being hollow, a rock shaft housed within said hollow side bar, a finger carried by the rock shaft, a pair of jaws pivoted to the side bars, and a lag 30 screw threaded to the rear bar.

CHARLES CHRISTIE.
